METHOD OF MAKING ORNAMENTAL MATERIAL

Max Sokoloff, Brooklyn, N. Y., assignor to Hy-Art Novelty Co. Inc., New York, N. Y., a corporation of New York

Application July 12, 1937, Serial No. 153,169

9 Claims. (Cl. 66—170)

My invention relates to a method of making ornamental materials and more particularly ball fringe or the like.

5 A ball fringe generally comprises a braid called a header strip having extended loops from which balls are suspended.

One of the objects of my invention is to form the header strip and connect the ball material thereto simultaneously.

10 Another object of my invention is to provide a method wherein the component parts of the ball fringe can be made and connected to each other on a single machine of standard construction.

Another object of my invention is to knit the 15 header loop to the ball material so as to dispense with the wire staple used at present as connecting means.

Another object of my invention is to provide a 20 method whereby a header strip may be formed and connected on each side of a warp rope so that two or more header strips can be formed simultaneously, and can take the ball material from a common source, namely the centrally disposed warp rope.

25 The economy resulting from such a method is obvious and production costs are reduced to a minimum.

Other objects of my invention will appear from the following description, it being understood 30 that the above statement of the objects of my invention is intended to explain and not to limit it in any manner.

Fig. 1 is an enlarged front view of two header strips connected to a central warp rope before 35 being cut into two lengths of ball fringe.

Fig. 2 is a greatly enlarged rear view of part 40 of Fig. 1.

Fig. 3 is a section on line 3—3 of Fig. 2.

Fig. 4 is a schematic view of the completed ball 45 fringe.

Referring to the drawing, H designates a header strip knitted with the warp threads 10 and the weft thread 11. Said weft thread is extended at 50 spaced intervals to form loops 12. The loops 12 are secured to a warp rope 13 in a manner to be hereinafter described.

On the opposite side of the warp rope 13 is disposed another header strip H1, similarly knitted with the warp threads 14 and the weft thread 15. The loops 16, formed from extensions of the 55 weft thread 15, are similarly connected to the warp rope 13, and such connections are staggered in relation to the connections of the header strip H to the warp rope 13.

55 The connection of the header strip to the warp

rope is illustrated in Fig. 2. Adjacent the warp rope 13 is a line of stitches 17 in the form of a chain, which is secured to the warp rope 13 at spaced intervals timed as the extended loops of the header strip. This chain 17 is composed of a thread 18 and a thin annealed wire 19 suitable for knitting. This may be wound on a single bobbin not shown and drawn off to produce the chain 17 adjacent the warp rope 13 which may be composed of a plurality of strands drawn from one or several bobbins and merely fed through the machine.

As the chain 17 is being formed adjacent to the warp rope 13, when the loop 12 is extended, it embraces the top portion of the loop and simultaneously the warp rope is moved to the left. The chain 17 then must encircle the warp rope 13 as at 20, in order to make the next stitch and in doing so it embraces the bottom portion of the loop 12. Thus the loop 12 is firmly secured to the warp rope 13 and the formation of the header strip H is continued until the next extended loop when the foregoing action is repeated.

The operation is repeated on the opposite side of the warp rope 13 securing the header strip H1 to the warp rope 13 in staggered relation to the connections of the header strip H as seen in Fig. 1.

The wire 19 is employed to lend rigidity to the chain 17, so as to insure a firm encircling of the warp rope 13 as well as a secure connection with the loop 12. However, either the thread 18 or the wire 19 might be eliminated.

After the structure as illustrated in Fig. 1 is formed on the knitting machine or otherwise, the warp rope is severed at the middle of each 35 bundle, as shown by the broken lines. The resulting product is two header strips with the section of warp rope connected thereto by the loops.

If the desired product be a tassel, it may be merely combed or otherwise treated. If a ball 40 fringe is desired, the header strips are placed in a steam vessel and the warp rope sections are thereby fluffed into globular shape.

I have shown a preferred embodiment of my invention but it is obvious that numerous changes 45 and omissions may be made without departing from its spirit.

I claim:

1. In a method of making ball fringe or the like, those steps which consist in forming a header strip, connecting a warp rope to said header strip at spaced intervals during said formation and cutting said warp rope intermediate said connections whereby sections of said warp rope 50 will be suspended from said header strip. 55

2. A method of making ball fringe or the like which comprises knitting a header strip, advancing a warp rope adjacent said header strip, connecting said header strip to said warp rope at regular intervals as part of said knitting operation and severing sections of said warp rope whereby said sections will be suspended from said header strip.
3. A method of making ball fringe which comprises advancing a warp rope, knitting a header strip adjacent and parallel to said warp rope, extending the weft threads of said header strip at regular intervals during said knitting operation, securing said extended weft threads to said warp rope, cutting said warp rope intermediate said connections whereby sections of said warp rope will be suspended from said header strip by said extended weft threads and forming said sections into balls.
4. A method of making ball fringe or the like which consists in knitting a header strip with extended loops at spaced intervals, simultaneously feeding a warp rope adjacent and parallel to said header strip, connecting said extended loops to said warp rope and severing said warp rope intermediate said connections whereby sections of said warp rope will be suspended from said extended loops.
5. A method of making a ball fringe which comprises forming a series of bundles in a warp rope by disposing a thread along said warp rope while encircling it at spaced intervals, simultaneously knitting a header strip with spaced extended loops, connecting the loops of said header strip to said warp rope by causing said thread to enter said loops, causing sections of said warp rope to be suspended from said header strip by severing each bundle transversely whereby half of one bundle and half of its adjacent bundle will be suspended by said extended loops from said header strip and forming said sections into balls.
6. A method of making ball fringe or the like which comprises knitting two header strips, advancing a warp rope between said header strips, connecting said header strips to said warp rope at spaced intervals as part of said knitting operation and severing sections of said warp rope whereby said sections will be suspended from said header strips.
7. A method of making ball fringe or the like which comprises knitting two header strips and simultaneously advancing a warp rope between them, extending the weft threads of said header strips at spaced intervals during said knitting operation, securing said extended weft threads to said warp rope, cutting said warp rope intermediate said connections whereby sections of said warp rope will be suspended from said header strips by said extended weft threads and forming the sections on both header strips into balls.
8. A method of making ball fringe or the like which comprises knitting two header strips with extended loops at spaced intervals, said loops being arranged on one of said header strips in staggered formation in relation to the loops of the opposing header strip, simultaneously feeding a warp rope between said header strips, connecting said extended loops on both said header strips to said centrally disposed warp rope and severing said warp rope intermediate said connection whereby two lengths of fringe will be produced and the sections of said warp rope will be suspended from said extended loops.
9. A method of making ball fringe which comprises forming a series of bundles in a warp rope by disposing a thread along said warp rope while encircling it at spaced intervals, simultaneously knitting a header strip on each side of said warp rope, said header strips being provided with extended loops, the loops of one header strip being staggered in relation to the loops of the other header strip, connecting said loops to said centrally disposed warp rope by causing said thread to enter said loops, causing sections of said warp rope to be suspended from said header strip by severing each bundle transversely whereby half of one bundle and half of its adjacent bundle will be suspended by said extended loops from one of said header strips while the other halves of said bundles will be suspended from the other header strip, and finally forming said suspended bundles into balls whereby two lengths of ball fringe will be produced.

MAX SOKOLOFF.
